No. 724,143.

PATENTED MAR. 31, 1903.

E. E. SULLIVAN.

PICKER MOTION FOR LOOMS.

APPLICATION FILED JUNE 11, 1902.

NO MODEL.

UNITED STATES PATENT OFFICE.

EDWARD E. SULLIVAN, OF FALL RIVER, MASSACHUSETTS.

PICKER-MOTION FOR LOOMS.

SPECIFICATION forming part of Letters Patent No. 724,143, dated March 31, 1903.

Application filed June 11, 1902. Serial No. 111,122. (No model.)

To all whom it may concern:

Be it known that I, EDWARD E. SULLIVAN, a resident of Fall River, in the county of Bristol and State of Massachusetts, have invented 5 certain new and useful Improvements in Picker-Motions for Looms; and I do hereby declare that the following is a full, clear, and exact description thereof, reference being had to the accompanying drawings, and to the letters of reference marked thereon, which form a part of this specification.

This invention has reference to an improvement in the picker-motions of looms whereby the shuttle is thrown from one side of the 15 loom to the other to lay the weft or filling threads. It is fully described in this specification and illustrated in the accompanying drawings.

Figure 1 is a side elevation showing my 20 mechanism attached to one end of the loom, a portion of the loom-frame and the lay partly in section, with a shuttle in position on the lay to be thrown. Fig. 2 is an end elevation of my mechanism with such parts of the frame 25 of the loom and lay as are necessary for illustrating my invention.

In the construction, A is the frame of the loom, B the lay, and C is the arch of the loom-frame.

30 D is the reciprocating shoe, which comes in contact with the shuttle E to throw it. This shoe slides back and forth on the guide-bar F, which latter is adjustably supported in a holder G, said holder being itself adjustably 35 held by the angle-bar H, said angle-bar being held in the bracket I, which is bolted to the side of the lay.

J is a bracket adjustably secured to the arch C, in which is slidably held the supporting-bar K. On the outer end of this supporting-bar is pivoted the bell-crank L, the lower arm of which is connected to the reciprocating shoe D by a flexible strap M. This strap may be made of leather, rubber, or other suitable material. The lever N is pivoted on the supporting-arm K, its outer end engaging the horizontal arm of the bell-crank, while its inner end is connected, through the connecting-rod O, to the foot P. It is squared at its lower 45 end and guided in the guide-plate R and held up in place by the closed spring S.

T is a shaft on the loom, preferably the main shaft, on which is mounted the crank V.

I do not wish to confine myself to the exact construction of the parts herein shown and 55 described, as they may be varied to suit the construction of the loom and the conditions under which the same is operated.

To enable others skilled in the art to use and apply my invention, I will now more fully 60 describe the operation of the same.

In a loom the warp is operated by the harnesses to open the shed as the lay moves backward. The shuttle E (shown on the lay in Fig. 1) has to be thrown through the opened 65 warp-shed from one side of the loom to the other while the lay is at or nearly at the farthest point of its backward stroke. As the cranks on the crank-shaft in their rotation operate the lay, I provide auxiliary cranks V, 70 one at each side of the loom, from which to obtain the motion for throwing the shuttle back and forth. Only one side of the loom and its mechanism are shown in the annexed drawings, the mechanism on the other side 75 being a duplicate of the same. As this crank V revolves it comes in contact with the foot P, giving it a quick downward motion, which is transmitted through the connecting-rod O and lever N to the bell-crank L, the downwardly-extending arm of which, being connected to the reciprocating shoe D by the strap M, gives it a quick forward motion at the proper time and throws the shuttle across the loom, which is returned by the duplicate 80 mechanism on the other side.

In practice the bell-crank L and the mechanism for throwing the shoe or picker-block D may be located at any convenient place on the loom-arch C, and if placed near its center 90 it gives a sufficient length to the flexible strap M to allow for any movement of the lay in beating up the weft-threads. When the shuttle is thrown across the loom, it strikes the shoe or picker-block D, carrying it to its extreme outward position, tightening the strap, and leaving the block in the proper position for receiving the required stroke to throw the shuttle back again across the loom.

I claim—

In a picker-motion for looms, in combination with the lay and shuttle, a guide-bar ad-

justably held in line with the lay to move it, a picker-block arranged to slide on said guide-bar, a bell-crank pivotally hung from the loom-frame, a flexible strap connection between said picker-block and the depending arm of said bell-crank, a lever pivotally hung with one end engaging an arm of said bell-crank, to throw it up, a rotating shaft-crank fixed to a rotating shaft engaging a foot at

each revolution, said rotating shaft and said foot, a connection between said lever and said foot, substantially as described.

In testimony whereof I have hereunto set my hand this 7th day of June, A. D. 1902.

EDWARD E. SULLIVAN.

In presence of—

HOWARD E. BARLOW,
S. L. GABRIEL.
